(57) **CLAIM**

We claim the ornamental design for a solar powered outdoor light, as shown and described.

DESCRIPTION

FIG. 1 is a perspective view of a solar powered outdoor light showing the new design;

FIG. 2 is a front elevational view, the rear, left and right side elevational views being mirror images thereof;

FIG. 3 is a top plan view thereof; and,

FIG. 4 is a bottom plan view thereof.

The dotted lines are for illustrative purposes only and form no part of the claimed design.

1 Claim, 4 Drawing Sheets

FIG. 2

FIG. 3
